United States Patent Office

Des. 175,090
Patented July 5, 1955

175,090

COMBINED BOTTLE AND TEETHING RING

Ralph W. Newton, Palmer, Mass., assignor to John H. Breck, Inc., Springfield, Mass., a corporation of Massachusetts

Application February 17, 1954, Serial No. 29,073

Term of patent 14 years

(Cl. D58—6)

Fig. 1.

Fig. 2.

Fig. 3.

To all whom it may concern:

Be it known that I, Ralph W. Newton, a citizen of the United States, residing at Palmer, in the county of Hampden and State of Massachusetts, have invented a new, original, and ornamental Design for a Combined Bottle and Teething Ring, of which the following is a specification, reference being had to the accompanying drawings forming part hereof:

Fig. 1 is a front elevational view of a combined bottle and teething ring showing my new design;

Fig. 2 is a side elevational view thereof; and

Fig. 3 is a rear elevational view thereof.

I claim:

The ornamental design for a combined bottle and teething ring, as shown.
